DESIGN FOR A CANDLE LAMP

Mitteldorf Straus, Richmond, Va.

Application May 22, 1936, Serial No. 62,763

Term of patent 7 years

To all whom it may concern:

Be it known that I, Mitteldorf Straus, a citizen of the United States, residing at Richmond, in the county of Henrico and State of Virginia, have invented a new, original, and ornamental Design for a Candle Lamp, of which the following is a specification, reference being had to the accompanying drawing, forming a part thereof.

Fig. 2 is a side elevational view thereof.

I claim:

The ornamental design for a candle lamp as shown.

In testimony whereof I have signed this specification.

MITTELDORFER STRAUS.
